ABSTRACT

A modular building system in which structural forms are generated from a family of modules which differ from each other in geometrical form and yet are sufficiently interrelated to facilitate their coordination. Each module is a three-dimensional open-ended form defined by equi-lateral square or rhombic face panels having the same perimeter or a composite thereof. All exposed edges of the modules in the family are of the same length so that several modules which are the same or different from each other may be joined together at their exposed edges or by their matching faces to develop diversified structural forms suitable for housing, storage, display and for many other architectural purposes.

MODULAR BUILDING SYSTEM

BACKGROUND OF THE INVENTION

This invention relates generally to architectural structures, and more particularly to a family of inter-related modules of different form which lend themselves to structural combinations to create a broad range of diverse architectural forms.

The term architectural structures, as used herein, is intended to encompass building forms, interior structures for buildings including furniture and fixtures and all multi-cellular structures defined by inter-related modules.

Interior architectural design is in large part concerned with the formation of cabinets, partitions, shelves and other structures serving for display, storage and a variety of other purposes and also to provide mounting surfaces for interior lighting systems. The form of an interior structure must be accommodated not only to the space in the chamber or area it is intended to occupy, but it must also conform to the functional and aesthetic requirements imposed thereon by the environment. The architect must, therefore, take into account whether the interior constitutes a residential, commercial, industrial or academic environment.

Thus, in the case of a factory requiring storage bins for manufactured goods, this requirement may be met by a uniform vertical array of box-like cells formed of wood or metal and serving a purely utilitarian function. But, should the environment be that of a school or home, a less symmetrical and a more aesthetic form of storage structure is generally more appropriate.

Hence, the present practice in creating suitable interior structures is to custom design and construct the cabinets and other structures which are dictated by the specific architectural needs of a given environment. The drawback to the practice is that custom design and construction is slow, inefficient and costly.

Considerable economies may be effected by the use of modular components that can be tailored to more or less conform to particular architectural requirements. Modules are known which can be joined together and stacked at different angles to define a variety of cellular structural configurations. But existing forms of structural modules have limited architectural possibilities. The reason for this is that modules of the type heretofore known are usually identical in form, and while such modules may be coordinated in various ways to develop a range of architectural patterns, the ultimate structure is still composed of identical cells. As a consequence, the modular structure, however complex, is inherently monotonous and lacking in interest. Also the fact that all cells are the same, limits the storage and display capabilities of the cellular system.

Modular principles have also been applied to building structures, such as the well known "Habitat" in Montreal, Canada. But here too, because the cells which compose the structure are essentially unvaried, limitations are imposed on the structures formed thereby, even though the positions of the cells relative to each other may be varied.

SUMMARY OF THE INVENTION

In view of the foregoing, it is the main object of this invention to provide architectural structures derived from a family of modules which are all distinctly different in geometric form and yet are sufficiently inter-related to facilitate their coordination.

More specifically, it is an object of this invention to provide a family of different modules, each of which is composed of equilateral square or rhombic face panels having the same perimeter or combinations thereof, to define open-ended, three-dimensional forms whose exposed edges all have the same length.

A significant feature of the invention is that despite differences in the geometric form of the modules, the fact that the exposed edges of all modules in the family have exactly the same dimension and that the faces thereof are either square or rhombic, makes it feasible to join together modules at their exposed edges and to combine or stack them at their matching faces to create diversified edifices suitable for housing, storage, display and a range of other functions.

Also, an object of the invention is to provide a family of modules which make possible the rapid construction and assembly of architectural structures efficiently and at relatively low cost.

Briefly stated, these objects are attained by a family of structural modules each constructed from equilateral square or rhombic face panels all having the same perimeter or a composite thereof to create an open-ended geometric form. The family of modules includes at least five distinct forms and structures may be assembled using one or more of these forms in combination.

The first module is composed of a pair of horizontal square panels and a pair of vertical square panels which are joined together. The second module is composed of a pair of vertical rhombic panels having a like-orientation which are joined to a pair of horizontal rhombic panels having a like-orientation. The third module is composed of a pair of vertical rhombic panels which are reversely-oriented with respect to each other and are joined to a pair of horizontal rhombic panels which are reversely-oriented with respect to each other. The fourth module is composed of a pair of horizontal rhombic panels having a like-orientation, joined to a pair of vertical square panels. The fifth module is composed of a pair of vertical rhombic panels having a like-orientation, joined to a pair of horizontal rhombic panels which are reversely-oriented with respect to each other to define one convolution of a helix.

The exposed edges of all modules in the family are of the same length so that modules may be joined together at their exposed edges or combined by their matching faces to create a broad range of diversified structural forms suitable for display, storage and many other purposes.

OUTLINE OF DRAWINGS

For a better understanding of the invention as well as other objects and features thereof, reference is made to the following detailed description of the invention to be read in conjunction with the annexed drawings wherein:

FIG. 1 is a view of a square face panel;

FIG. 2 is a view of a rhombic face panel;

FIG. 3 is a perspective view of the first module in a family thereof in accordance with the invention;

FIG. 4 is a perspective view of the second module in the family;

FIG. 5 is a perspective view of the third module in the family;

FIG. 6 is a perspective view of the fourth module in the family;

FIG. 7 is a perspective view of the fifth module in the family;

FIG. 8 is a perspective view of an example of an interior structure composed of modules derived from the family thereof;

FIG. 9 is a perspective view of another example of an interior structure composed of modules derived from the family thereof;

FIG. 10 is a perspective view of yet another example of an interior structure composed of modules derived from the family thereof;

FIG. 11 is a perspective view of still another example of an interior structure composed of modules derived from the family thereof.

DESCRIPTION OF THE INVENTION

Referring now to FIGS. 1 and 2. There is shown the two basic face panels from which the family of seven modules is derived. FIG. 1 shows a square panel 10, having equilateral sides at right angles to each other, and FIG. 2 shows an equilateral rhombic panel 11 having oblique angles. The length of each side of the equilateral square panel is equal to the length of each side of the equilateral rhombic panel. Thus all panels have 30 identical perimetric dimensions.

The rhombic panel shown has two opposing 60° acute angles and two opposing 120° obtuse angles. It is to be understood, however, that rhombic panels having other angular relationships may be used, such as a panel having two opposing 45° acute angles and two opposing 120° obtuse angles. The advantage of a 60°-120° panel is that the diagonal thereof which divides the panel into two equilateral triangles is equal in length to the length of the sides, thereby making it possible to join the edge of a module to this diagonal. Rhombic panels other than 60°-120° panels are of particular value in creating surfaces of more gradual slope.

In accordance with the invention a family of seven basic modules of different geometric form is created by means of the equilateral square or rhombic panels or a composite thereof to create three-dimensional, open-ended forms all having a rectangular cross-section.

As shown in FIG. 3, the first module, generally designated as MI, is composed of a vertical and a horizontal pair of square face panels 10 which are joined together at right angles to each other to define an open-ended structure having a cubic shape. The manner in which the panels of the five modules are joined together depends on the nature of the panel material. In practice the joints, in the case of wood, may be of the type commonly used in woodworking. In the case of metal or plastic panels, metal or plastic bonding or welding techniques may be used, or suitable junction clips or brackets may be provided. The manner in which the face panels are joined together forms no part of the present invention.

As shown in FIG. 4, the second module, generally designated as MII, is composed of a vertical and a horizontal pair of rhombic panels 11 which are joined together at right angles to each other to define an open-ended structure in which the panels in the vertical pair

thereof have a like-orientation and the panels in the horizontal pair have a like-orientation. Thus the open ends of the second module lie in a plane which is inclined relative to the vertical axis.

Referring now to FIG. 5, there is shown the third module MIII which is composed of a pair of vertical rhombic panels 11 which are reversely-oriented with respect to each other and are joined to a pair of horizontal rhombic panels 11 which are reversely-oriented with respect to each other.

Referring now to FIG. 6, there is shown the fourth module MIV which is composed of a pair of vertical square panels 10 joined to a pair of horizontal rhombic panels 11 having a like-orientation with respect to each other.

Referring now to FIG. 7, there is shown the fifth module MV which is composed of a pair of vertical rhombic panels 11 having a reverse-orientation with respect to each other, joined to a pair of horizontal rhombic panels 11 which are like-oriented with respect to each other, so that in this instance the form is not continuous but assumes the shape of a single convolution of a helix. As this fifth module may be connected to a series of identical fifth modules to create a multi-turn helical form; the number of turns being equal to the number of modules, one can, by means of this module, create elongated ducts having a rectangular cross-section.

The sixth module (not shown) is a variation of module MV and is also a spiral. In module MV, the horizontal rhombic panels have a like-orientation whereas in module MVI, the horizontal as well as the vertical rhombic panels have a reverse-orientation with respect to each other. The seventh module (not shown) is a variation of module MIV. But in module MVII, which has a screw formation, the two vertical square panels are joined to a pair of horizontal rhombic panels having a reverse-orientation with respect to each other, rather than a like-orientation.

As shown in FIGS. 8, 9, 10 and 11, one may assemble the modules to create forms in varying degrees of complexity to provide a broad range of diverse structural configurations. The modules in the family may be connected at their exposed edges, for all edges have exactly the same dimensions. The modules may be also connected in end-to-end relation, in side-by-side relation and in stacked relation, for wherever adjoining modules have congruent rhombic or square faces they may be bonded or connected.

While the modules are all open-ended, in some instances, the ends may be enclosed and in other cases left open to meet particular requirements. The resultant edifices may be extended by suitable modules in the vertical direction, or in the horizontal direction, and in some instances because of the rhombic formation the structure may be skewed to afford further variations in form. Modules MV, MVI and MVII have both left and right-handed conditions so that any of these spiral forms may twist either clockwise or counter-clockwise.

The panels from which the modules are fabricated may be wood, plastic, fiberglass, metal or any other material appropriate to the intended use. A great variety of possible applications exist. For example, toys may be built of panels whose sides are only 2 or 3 inches long. At this size, the modules may be molded intact of plastic. Larger sizes may be used to make light-weight fix-

tures, furniture, containers, container racks and compartmentalized storage areas or to develop three-dimensional shells for boats and airplanes. A still larger size module with say a two foot edge, may be used to create furniture both of the built-in and free standing type.

Whole buildings may be created using large size modules forming the structural and architectural elements, including ceilings, floors, walls, ducts and chases as well as window frames and other framed openings. Interior and exterior architecture may thus be thoroughly integrated. At these sizes, the modules may be manufactured as components and assembled on the site, thereby reducing transportation costs and site storage and movement problems. The same modules may be created on the job site through the use of forms which are negatives of the final product.

While there has been shown preferred embodiments of the invention, it will be appreciated that many changes may be made therein without departing from the essential spirit of the invention.

We claim:

1. A structure formed by interrelated modules derived from a family of five modules which are selectively connectable in end-to-end, side-by-side and in stacked relation, each module being constructed from four face panels selected from a class consisting of square and rhombic panels to create an open-ended geometric form, all sides of said square and rhombic face panels having the same dimension whereby the exposed edges of all modules have the same dimension and some modules derived from said family may be joined together at their edges and other modules at

their congruent faces, said family of modules comprising:

- A. a first module composed of a pair of horizontal square panels, joined at their edges to a pair of vertical square panels to define a cubic volume;
  - B. a second module composed of a pair of vertical rhombic panels having a like-orientation joined at their edges to a pair of horizontal rhombic panels having a like-orientation;
  - C. a third module composed of a pair of vertical rhombic panels which are reversely-oriented with respect to each other and are joined at their edges to a pair of horizontal rhombic panels, which are reversely-oriented with respect to each other;
  - D. a fourth module composed of a pair of horizontal rhombic panels having a like-orientation which are joined at their edges to a pair of vertical square panels; and
  - E. a fifth module composed of a pair of vertical rhombic panels having a like-orientation whose edges are joined to a pair of horizontal rhombic panels having a reverse-orientation to define one convolution of a helix.
2. A structure as set forth in claim 1, wherein said face panels are all formed of synthetic plastic material.
3. A structure as set forth in claim 1, wherein said face panels are all formed of metal.
4. A structure as set forth in claim 1, further including end panels attachable to the exposed edges of said face panels to enclose at least one of the modules in the structure formed thereby.
